UNITED STATES PATENT OFFICE.

EDWIN CYRUS WASHBURN, OF NEVADA, MISSOURI.

COMBINED GATE ROLLER AND HINGE.

SPECIFICATION forming part of Letters Patent No. 330,648, dated November 17, 1885.

Application filed September 6, 1884. Serial No. 142,400. (Model.)

To all whom it may concern:

Be it known that I, EDWIN CYRUS WASHBURN, of Nevada, Vernon county, Missouri, have invented a new and Improved Combined 5 Gate Roller and Hinge, of which the following is a full, clear, and exact description.

My invention consists in a gate roller and hinge for farm use, constructed to give a firm support to the gate, as hereinafter described 10 and claimed.

Reference is to be had to the accompanying drawings, forming part of this specification, in which similar letters of reference indicate corresponding parts in both figures.

15 Figure 1 is a front elevation, partly sectional, of the roller and hinge as applied to a gate, and Fig. 2 is a side view of the hinge.

A A' are two wrought-iron plates, receiving between their upper portions the roller B 20 upon a cross-pin or axis, a. Beneath the roller the back plate, A', is bent to form a flange, b, that is riveted to plate A, so as to hold the two plates firmly together, and from the flange the lower end of the plate A' is bent outward 25 to form a socket or recess, c, that receives the eye of an eyebolt, d. A pin, e, passing vertically through the plate A' and eye of bolt

d, retains the latter in place and allows the hinge movement. The lower ends of plates A A' form a jaw, f, which, when the device is in 30 place receives the upper edge of the gate-board below the one resting on the roller, thereby holding the gate more steadily.

The screw-pin is to be screwed into the gate-post, as shown. The second board of the gate 35 rests on roller B, and the jaw f is set over the third board. The gate thus hung can be rolled back in the usual manner, and it can also be swung on the hinge.

The hinge and the plates forming the body 40 being of wrought-iron, the whole device is of the most substantial and durable character.

Having thus described my invention, I claim as new and desire to secure by Letters Patent—

The herein-described gate roller and hinge, 45 consisting of the plates A A', riveted together, (the plate A' being bent to form the socket c,) the roller B, and the bolt d, pivoted in the socket of plate A', as set forth.

EDWIN CYRUS WASHBURN.
